SIGNOR TO HARMON S. PALMER HOLLOW CONCRETE BUILDING
BLOCK COMPANY, OF WASHINGTON, DISTRICT OF COLUMBIA, A
CORPORATION OF VIRGINIA.

BUILDING-BLOCK.

No. 800,875.

Specification of Letters Patent.

Patented Oct. 3, 1905.

Application filed March 16, 1905. Serial No. 250,466.

To all whom it may concern:

Be it known that I, HARMON S. PALMER, of Washington, in the District of Columbia, have invented a certain new and useful Improvement in Building Blocks or Stones; and I do hereby declare that the following is a full, clear, and exact description thereof, reference being had to the accompanying drawings, in which—

10 Figure 1 is a perspective view of a building-block embodying my invention. Fig. 2 is a cross-section of the same in position in a wall, and Fig. 3 is a similar view of a different construction embodying my invention.
15 The object of my invention is to so construct building-blocks, especially those of artificial stone, that discoloration of the surface of the blocks from water will be prevented and at the same time a stronger and 20 better-looking wall obtained; and to this end my invention consists in the block or stone constructed substantially as hereinafter specified and claimed.

25 Walls or buildings of artificial stone or cement or concrete building-blocks as heretofore made by reason of the percolation of water through the stones and the dissolving out by the water of the mortar or cement between the stones are defaced or stained by 30 streaks or lines down the face or outer surface of the stone, the water passing out between the joints of the stones dissolving and carrying with it the salts and particles of the cement or mortar in the joints. The outward 35 passage of the water between the joints, it may be remarked, instead of its percolation down through the stones is due to the failure of the stones to set level, so that their upper sides incline outward and downward, with the natural 40 result that the water will flow over their upper sides outward and thence down over the face or outer surface of the stones.

45 In the carrying of my invention into practice in one embodiment thereof I form the upper side of the stone or block with a depression that extends from each side of the block or stone inward and downward, which depression, as shown, may be in the form of a concavity *a*, so that the edges of the block or 50 stone at the sides thereof are higher than any other point or surface on the upper side of the block, the result being that water per-

colating or passing through one stone or block to the one below it will gravitate or pass away from the sides of the block or stone 55 toward the middle of the top thereof, and thus be prevented from passing out between the joints to the sides of the stone or block.

As a matter of convenience in placing the stones or blocks in the wall both top and 60 bottom thereof are provided with the depressions; but, if desired, the one depression may be employed, in which event of course care will be required in setting the block to get the depression uppermost. The presence 65 of the depression in the block or stone, besides preventing the soiling or staining of the face of the block by the dripping or passage over it of the dissolved mortar, is also of importance in that as a cavity or chamber is 70 thereby provided between the blocks a quantity of mortar or cement can be employed that will make a strong bond and yet the appearance of the wall will not only not be marred or objectionably affected by reason of 75 the presence of the mortar or cement, but, on the contrary, a clean fine joint can be secured, because the edges of the abutting blocks or stones can be placed closer together than is possible where the abutting surfaces 80 are flat surfaces with a body of cement or mortar between them of uniform thickness.

In using blocks with depressions or concavities it is important that the cement or mortar used be not harder or less porous than the 85 blocks, for it will be evident that if water after percolating through a block encounters cement or mortar, through which the water will not readily pass, the water will flow outward between the under side of the block and the 90 upper surface of the cement or mortar in the joint to the face of the wall, and thus result in the conditions which it is the object of my invention to obviate. Should a mortar or cement be employed harder or less porous than 95 the blocks, the object of my invention can be secured by making the bottom of the block bulging or convex—that is to say, by inclining such bottom from the sides inward and downward, as illustrated in Fig. 3. With 100 this arrangement it will be apparent that the upper surface of the mortar or cement in the joint will incline inward and downward, and the water failing to percolate through the mor-

tar or cement will gravitate inward and downward away from the outer surface of the block.

Hollow artificial blocks or stones, which are 5 stones perforated by one or more vertical slots or openings, are admirably suited for the employment of my invention, because in the vertical holes or openings in the central portion of the block there exist passages for the water 10 that flows inward.

It is to be understood that I do not limit myself to the employment of any particular form of depression in the block or stone, as there may be variations of this which will involve 15 no departure from the principle of my invention.

Having thus described my invention, what I claim is—

1. A building block or stone having a mortar-engaging surface which, with the mortar, forms a downwardly and inwardly inclined water-passage all portions of such passage from the outer surface of the block being lower than the beginning of such passage at the 25 outer side of the block.

2. A building block or stone having a mortar-engaging surface, which, with the mortar, forms a downwardly and inwardly inclined water-passage and provided with an internal, 30 vertical opening to which the passage delivers water the highest point of such water-passage being at the outside of the block whereby water is prevented from passing to the outer face of the block.

35 3. A building block or stone having a mor-

tar-engaging surface that is lower at one point than at another and inclines between such points to cause water to pass downward and inward and having an internal, vertical opening that leads from the lowest point of 40 such surface.

4. A building block or stone having a depression or cavity in its side that abuts or adjoins another block or stone and having an internal, vertical opening that leads from the 45 lowest point of the depression.

5. A building block or stone, having a dished upper side all points of the dished surface within the block being lower than the point where the dishing begins at the outer 50 side of the block.

6. A building-block of artificial stone, vertically perforated, and having a dished upper surface from whose lowermost point the perforation starts.

7. A wall composed of stones, one above another, and mortar or cement between them, with the abutting surfaces of mortar and stone inclined inward and downward such abutting surface from the outside of the stone inward 60 being successively lower and lower so that within the stone there are no points of the abutting surfaces higher than at the outer face of the stones.

In testimony that I claim the foregoing I 65 have hereunto set my hand.

HARMON S. PALMER.
